APPARATUS FOR RECONDITIONING THE EXTERIOR OF CONTAINERS

Samuel F. Kimball, Portland, Maine, assignor to
 The Portland Company, Portland, Maine, a
 corporation of Maine

Application October 11, 1933, Serial No. 693,132

7 Claims. (Cl. 198—183)

This invention relates to machines for reconditioning containers and particularly for that part of the reconditioning that has to do with the exteriors of barrels or casks.

5 Aside from the inherent problem of thoroughly cleansing such containers automatically, especially where they have been used for oil and like materials, real operating problems exist, first, in keeping the washing and rinsing fluids separate so that the maximum use may be had of each; second, in maintaining the operation of the machine while the washing and rinsing fluids are being renewed; and third, in adapting the machine to practical working conditions.

15 The need for such a machine and such service has long been recognized but although attempts have been made to provide a machine to perform such work, most of the reconditioning is still done by manual labor.

20 My concept solves the problems involved by providing for a machine in which the washing and rinsing fluids are kept separate. At the same time, I provide alternate tanks for both fluids so that one may be used while the fluid in the other is being prepared, or the tank refilled or flushed out. I also carry the containers through a driven spray rather than through tanks full of liquid, thus permitting the fluids to be kept in circulation. With my invention, therefore, containers 25 may be reconditioned without any manual handling as the containers will be automatically entered, carried through and discharged from my machine.

These and other features will be apparent from 30 the accompanying drawings:

35 Fig. 1 is a plan view of an outside washer in accordance with my invention partly sectioned with conveyor and container releasing mechanism omitted to expose the fluid circuits in the interior.

40 Fig. 2 is a side elevation of the same, broken away to expose the interior.

Fig. 3 is an end view of the same from the left of Fig. 1.

45 Fig. 4 a sectional view through the washing station on line 3—3 of Fig. 2.

Fig. 5 a side elevation of the drying station.

Fig. 6 a fragmentary plan view of the barrel controls in the drying station.

50 Fig. 7 is a fragmentary view of a scrubbing unit.

Fig. 8 is an enlarged view of the barrel release.

Fig. 9 is a detailed vertical view of the controls therefor.

55 Fig. 10 is a cross section of the container conveying and rotating system.

Fig. 11 is a partly sectional view of the container conveyor showing in detail a cross member.

Fig. 12 is a view of the drain valve.

Fig. 13 is a side view of the barrel release, and Fig. 14 shows in detail the dirt screen surrounding the drains.

Fig. 15 is an enlarged partly fragmentary section through the washing station.

In such a washing machine I provide a base generally indicated at 1 and an upper portion 10 or framed superstructure 2 including a washing station generally indicated at W and a rinsing station at R and a drawing station at D. The base 1 is provided with tanks 3 and 3^a separated by a partition 3^b for washing fluid and tanks 4 and 4^a separated by the partition 4^b for rinsing fluid. Each of these tanks is preferably provided with suitable heating means 5 such as shown in the tanks 3 and 4 subject to thermostatic controls such as at 6.

20 Each tank is also provided with valve controlled inlets 7 having float controlled valves 1^a and valve controlled outlet drain pipes 8. Valve controlled suction outlets 8^a lead from each tank to washing fluid and rinsing fluid pumps 9 and 9^a respectively.

25 In each of the tanks I provide scum traps 12, always open to drain as at 13.

Near the front of the washing station and near the rear of the rinsing station the floor F is provided with drains 11^a. A valve 11 is pivoted in each drain and the pivots are extended to form the handle 10 for the valve 11 adapted to be positioned to direct the liquid into either of the washing tanks 3 or 3^a, and the handle 10^a by which 30 the other valve 11 may be positioned to return the rinsing liquid into either of the rinsing tanks 4 or 4^a.

35 By these controls, it will be seen that any tank may be isolated at any time when the fluid therein is unsuited for further use without interfering with washing or rinsing operations by turning the valve 11 to direct the flow into the alternate tank and by closing the valve in control of the suction outlet 8^a for the tank to be isolated as 40 will be apparent from Figs. 1 and 12. When so isolated, it may be drained, flushed out, refilled, and heated so as to be in proper condition when 45 its alternate needs attention.

45 From the pumps 9 and 9^a fluid conduits or 50 mains 14 lead to a series of shower devices in the washing and rinsing stations W and R, each shower device having an arm 15 to spray the sides of a container and crossed spray bars 16 disposed to discharge on the ends of the containers.

The containers C are placed in the machine on the slide A, and are there held by the barrel control arm 17 and the guide A'.

The conveyor generally indicated by C consists 5 of a pair of chains 19 carried by the sprockets 20 and 21^a. At suitable intervals, as is shown in Fig. 10, links in the chains 19 are provided with fixed uprights 60 to which are secured yokes 61 to receive cross members C' and C².

10 Each of the cross members C' and C² is provided with axle arms C⁴ (see Fig. 11) on which are mounted for independent rotation bearings 62 formed with a flange 63 which serves as a wheel flange with the track 18 on each side of the apparatus and with a flange 64 defining with the flange 63 a groove for the yokes 60 in which the bearings 62 are loosely mounted.

15 The axle arms C⁴ of the cross members C², as shown in Figs. 10 and 11, are provided with discs 20 or sprockets C³.

20 By this construction, the movement of the chain and the travel of the bearings 62 along the tracks 18 do not rotate the cross members. As I desire to have the containers rotate, I provide 25 an auxiliary belt or chain 21 driven by any suitable means and which contacts and rotates the discs or sprockets C³ and the cross members C² at any desired speed.

30 At predetermined intervals the barrel feeding mechanism, to be later described, releases a barrel to position where it will be picked up by the conveyor.

35 The conveyor consists of a pair of chains 19. The chains are driven by a motor (not shown), rotating the sprockets 20 on a shaft 20^a, suitably mounted in the superstructure 2. Near the front end of the apparatus are sprockets 21^a on a shaft 21^b. The shaft 21^b is journaled in bearings 30 in blocks 31 which are slidably confined in guides 40 on the superstructure 2. The forward ends of the blocks 31 are secured to weights 34 to keep the chain 19 taut.

45 The floor F is provided with a partition F' to prevent the mingling of the washing and rinsing liquids. Before the washed containers pass over the partition F' into the rising station, they are drained. This is accomplished by lowering the conveyor supporting track 18 to a lower level through a zone D. The conveyor is forced to follow the track 18 by a depressor D' disposed to contact the ends of the cross members C' and C². The enlarged ends C³ are thereby carried out of contact with the belt 21 stopping rotation of the cross members C² and the containers.

55 The drainage in each station flows from the partition F' towards the drains 11^a whence it is directed to the desired tank 3-3^a or 4-4^a by the valves 11. The drains are covered by a box-like shield indicated as at 11^b in Fig. 15. Beneath this shield there is a sloped member 11^c over the drains 11^a, in the inner end of which are mounted the scum retaining member 23 and the screens 24 and 24^a to retain mud and other dirt.

65 The container delivering mechanism may be best seen in combination in Fig. 15, and in detail in Figs. 8, 9 and 13. This comprises cams 38 mounted on the sprocket shaft 21^b between the sprockets 21^a and bearings 30. Forwardly of the sprocket bearings 30 bell crank levers 17 are pivoted to the blocks 31. The levers 17 are provided with cam engaging portions 17^a and two levers 17 are connected by a bar 17^b. The cam 38 rotates with the sprockets 21^a, and on each 70 rotation permits the bar 17^b to drop from a posi-

tion holding containers on the slide A to a position permitting the container to roll forwardly on to the conveyor between the cross members C' and C². As the arm 17 is raised, a container is carried on to the conveyor, and the cross bar 17^b is moved to hold the next container on the slide until it is properly positioned on the conveyor in turn.

75 Reconditioning, in many instances, implies painting or other refinishing, and inasmuch as 10 for that step the containers must be dry, I have provided a drying zone to ensure that the containers will be thoroughly dried in the shortest possible time. The size of this chamber will depend largely on the speed with which the containers are passed therethrough and through the 15 washing and rinsing stations. In the drawings I have shown a drying unit of capacity to hold three containers, but as description of larger capacity would be repetition, I limit my description 20 to the different features of the illustrative form.

The drying unit preferably consists of a casing or oven 40 and an inclined floor 41 which permits the barrels to roll as they travel through the oven. Heating means 42 for the oven are 25 provided. The entrance is provided with a swinging door 43 and the exit has a door 44. These doors while closed will retain the containers in the oven and keep other containers from entering. Within the casing 40 container stops 45 are 30 positioned. The stops 45 are rods extending transversely of the oven and are adapted to lie against the containers to hold them on the inclined floor 41 for a period sufficient to ensure their dryness when delivered from the oven. 35

The doors 43 and 44 are normally held closed and the container stops 45 are normally held in barrel engaging position by a bell crank lever 49 pivoted to a shaft 51, and to the long arm 49^a of which is connected a weight 50, 50^a or 50^b as 40 of the case may be.

The doors 43 and 44 are swung to open position and the container stops lowered to permit the passage of the containers through the oven by means of the connecting rod 46 which is actuated by the crank 53 on the sprocket shaft 20^a. The connecting rod 46 is positioned off center from the sprocket 20 and is eccentrically connected to a disc 47 controlling the barrel exit door 44, to discs 47^a, one controlling each of the 50 container stops 45, and a disc 47^b controlling the container entrance door 43.

55 Each disc carries a catch 48 adapted to engage a lug 49' on the short arm 49^b of the bell crank lever 49 on predetermined rotation of its disc which rocks the bell crank lever against the force of the weight 50, 50^a or 50^b.

The bell crank lever 49 is rigidly connected to the container stops 45 by the bar 45^b which lies parallel to the container stop 45 to which it is 60 rigidly connected by the arm 45^a so that the stops 45 pivot with the bell crank lever. The bar 45^b is connected to the bell crank 49 at 45^c and finds bearing in the block 45^c on the shaft 51 on which the bell crank lever pivots.

65 The opening of the entrance door, the successive movement of the containers through the oven, and the opening of the exit door are synchronized by initial positioning of the discs relative to the connecting rod 46 so that on predetermined movement thereof, desired contact of the catch 48 on the discs and the lug 49' on the bell crank 49 is effected. (See Fig. 5.)

70 In the case of the doors, suitable connections lead directly from the bell crank lever 49 to the 75

doors to swing them against the forces of the weights 50—50^b exactly as the container stops 45 are pivoted. The stops are pivoted or carried downward to permit the barrels to roll along the oven floor when the connecting rod 48 rotates the discs 47, 47^a, 47^b to position where the catch 48 engages the lug 49' to pivot the bell crank lever 49 against the weights 50.

When the discs have revolved to an extent sufficient to permit each container to advance to its next position, the catch 48 and lug 49' are disengaged and the weight 50 carries the bell crank lever again to the position of Fig. 5 in which the containers are stopped and doors closed.

15 The drying unit may, of course, be made separately or integrally with the washing machine, but it is synchronized definitely therewith in reconditioning the barrels with the maximum efficiency and the minimum length of time so that 20 they may be refinished by painting.

25 My invention permits container exteriors to be thoroughly reconditioned at a minimum cost and is well adapted to even the most unfavorable conditions and may be adjusted to solve any operating condition. My invention may be otherwise formed and modified without departing from the spirit thereof if within the limits of the appended claims.

What I therefore claim and desire to secure 30 by Letters Patent is:—

35 1. A conveyor for barrels or like containers comprising spaced endless chains, a plurality of pairs of transverse members connecting said chains and rotatable independently thereof and of the container travel, each of said pairs being 40 adapted to support a container on its side, and means to rotate only one of the transverse members of each pair independently of the conveyor travel.

45 2. A conveyor for barrels or like containers comprising spaced endless chains, a plurality of pairs of transverse members connecting said chains and rotatable independently thereof and of the container travel, each of said pairs being 50 adapted to support a container on its side, means to rotate only one of the transverse members of each pair independently of the conveyor travel, and means rendering said last named means inoperative during a portion of said travel.

55 3. A conveyor for barrels or like containers comprising a track, spaced endless chains, a plurality of pairs of rotatable transverse members connecting said chains, each of said pairs being adapted to support a container on its side, track

engaging wheels mounted on each of said transverse members for rotation independently thereof, and means to rotate one of the transverse members of each pair independently of the conveyor travel, and means rendering said last named 5 means inoperative during a portion of said travel.

4. A conveyor for barrels or like containers comprising a track, spaced endless chains, a plurality of pairs of rotatable transverse members connecting said chains, each of said pairs being 10 adapted to support a container on its side, track engaging wheels mounted on each of said transverse members for rotation independently thereof, and means to rotate one transverse member of each pair, said means comprising a driven means 15 on said transverse member and driving means disposed normally to contact said driven means, and means rendering said rotating means inoperative, said means comprising a concaved portion of said track disposed below the plane of adjacent 20 track portions a sufficient distance to ensure the disengagement of said driven and driving means and means to force said track engaging wheels onto said concaved track portion.

25 5. A conveyor for barrels or like containers comprising a track, spaced endless chains, a plurality of spaced yokes carried by said chains, a plurality of pairs of transverse members, each of said members including axle arms and a track engaging wheel mounted on each of said arms 30 for rotation independently thereof, each of said wheels including a pair of spaced flanges defining a recess for loosely receiving one of said yokes, each of said pairs of transverse members being 35 adapted to support a container on its side, and means to rotate one of said transverse members of each pair comprising a driven member rigidly mounted on an axle arm thereof, and a driving member disposed normally to contact said driven member to rotate the transverse member independently 40 of the travel of said conveyor.

6. The structure of claim 5 and means to disengage the driving and driven members to stop rotation of said transverse member thereby.

45 7. The structure of claim 5 and means to disengage the driving and driven members comprising a concaved portion of said track disposed below the plane of adjacent track portions a sufficient distance to ensure the disengagement of said members when said wheels are traveling 50 through said concaved portion, and a depressor mounted above said track to force said wheels into said concaved track portion.

SAMUEL F. KIMBALL.
